Primary Examiner—James Gandy*Assistant Examiner*—Cathron B. Matta*Attorney, Agent, or Firm*—Paul M. Denk[57] **CLAIM**

The ornamental design for the container separator with scoop, as shown and described.

DESCRIPTION

FIG. 1 is an isometric view of the container separator with scoop of this invention;

FIG. 2 is a top plan view thereof;

FIG. 3 is a bottom plan view thereof;

FIG. 4 is a front view thereof;

FIG. 5 is a rear view thereof;

FIG. 6 is a left side view thereof; and,

FIG. 7 is a right side view of the invention.
